UNITED STATES PATENT OFFICE.

ISAAC MCKIM CHASE, OF WASHINGTON, DISTRICT OF COLUMBIA.

CONSERVATORY FOR PAPER.

SPECIFICATION forming part of Letters Patent No. 397,276, dated February 5, 1889.

Application filed December 10, 1887. Serial No. 257,561. (No model.)

To all whom it may concern:

Be it known that I, ISAAC MCKIM CHASE, a citizen of the United States, residing at Washington, in the District of Columbia, have invented certain new and useful Improvements in Conservatories for Paper, &c.; and I do hereby declare the following to be a full, clear, and exact description of the invention, such as will enable others skilled in the art to which it appertains to make and use the same.

My invention relates to improvements in conservatories for rolled paper, muslin, or other fabrics, and the object is to provide an apparatus in which paper, muslin, or other fabrics wound on rolls can be preserved and protected from dust, &c.; also, to prevent the waste occasioned at present in cutting off sheets or any desired part of the roll; also, to produce means by which said paper or fabrics can be cut from the roll in a straight and regular manner without the use of a rule or straight-edge. Furthermore, to furnish means by which short as well as long rolls of paper, fabrics, &c., can be placed in adjustable bearings supporting said rolls. Another object is to adjust the tension of the material as desired, and, finally, to furnish a ready means for measuring the desired width of the sheets before cutting them off without the necessity of a rule and at the same time when drawing out the paper.

With these ends in view my invention consists in a receptacle or box having a hinged cover or its equivalent for placing the material wound on a roll in position, and securing to the front side of said receptacle a rail or bar having a groove or channel in its upper face, into which a knife can be inserted, and serves as a guide to cut the paper or fabric in a perfectly straight manner. It also consists in arranging an adjustable bearing in the receptacle to accommodate different lengths of rolls, and it finally consists in the construction of certain details and arrangement of parts, as will be more fully described hereinafter, and specifically pointed out in the claims, reference being had to the accompanying drawings and the letters marked thereon.

Like letters indicate similar parts in the different figures of the drawings, in which—

Figure 1 represents a perspective view of a receptacle for containing rolls of paper, &c., according to my invention. Fig. 1^a is a cross-section of the same on line *xx* of Fig 1. Fig. 2 is a perspective view of a case, cabinet, or secretary containing a series of said receptacles. Fig. 3 is a front view of a modification of Fig. 1 arranged for several rolls and partly in section. Fig. 4 is a vertical cross-section of the same on line *yy* of Fig. 3. Fig. 5 is a longitudinal section of another modification. Fig. 6 is a vertical cross-section of the same in line *zz* of Fig. 5. Fig. 7 is a detail view of a roller for the paper, &c.

In the drawings, A represents a receptacle of any suitable size and material, having a hinged cover, B, through which the paper, fabric, and the like is inserted in place in its journals *b*, which may be secured to the ends or be detachable. The front side of the receptacle has the rail C secured to it, and is provided with a groove or channel, *c*, which serves to guide a knife or other cutting-blade in cutting off the paper, &c., when drawn out to the desired length. At about a central part of the front side is placed a hook, *a*, to which the looped end of a tape-line or its equivalent is attached to measure off the desired length of sheet. A movable partition, D, may be provided, having an adjusting-screw, *d*, in it for supporting tracing-paper or muslin of different lengths upon it, and in this case a similar screw may be used, as at *d'*, for holding the opposite end of the roll.

In the modification shown in Figs. 3 and 4 the receptacle is represented for three rolls placed above each other. In this instance the front side is made in three parts for inserting any roll separately. These parts E are held in place by the turn-buttons *e*, and are provided with the cutting-rail C, with groove *c*. If desired, this rail and groove may be lined with metal. The cover B is secured to the receptacle, and the rolls of paper, fabric, or other material are inserted as follows: At each end of the receptacle is placed a liner, *f*, provided with a dovetailed piece, *g*, and said groove forms, with the dovetail piece *g*, the journal for the bar or rod *h*, upon which the paper, &c., is rolled. After the insertion of the roll and the piece *g*, the front, E, is placed in its position and the turn-button *e*

revolved half a revolution, which locks the front. The end of the paper is passed through the front, as shown at *x*, and if it is desired to increase the tension the clamping-piece *F* can be adjusted down upon the paper, &c., and is ready for cutting. To suit different lengths of material, a partition, *D*, may be secured to the top by wood-screws or otherwise, and a pivoting-screw, *d*, can be provided; or said screws may be inserted in the ends of the receptacle for supporting the rolls.

In the modification shown in Figs. 5 and 6 a single roll-receptacle is shown, having its cover hinged, and the movable partition *D* is held in place by a spring, *G*, supported in a recess or cavity and presses with its opposite end against the cover of the receptacle. The pivoting-screws are in this case operated through the openings *i* in the ends of the receptacle. The lower sides of the partition can be held in place by inserting them in suitable grooves for their reception, as at *k* in Fig. 6.

In Fig. 2 is represented a series of the receptacles placed above each other, and they may be constructed on a stand, as shown by the dotted lines, or in the form of a cabinet, secretary, or any suitable piece of furniture. The rollers upon which the rolls of paper, fabric, &c., are wound may be made in the form of a spool, as seen in Fig. 3, having flanges at the ends; or they may consist of a rod of metal, *H*, upon which the flanged spools *I* are secured, and, if desired, one of the spools may be made adjustable to suit different lengths of material, as shown in Fig. 7.

The operation is as follows: The paper, fabric, or like material is placed in position in the receptacle, and the end of said material extending over the groove *c* in the rail, a knife or cutting blade is inserted in the groove and drawn through the material with its cutting-edge being guided by the said groove, thus forming a straight cut. The material can be cut to any desired width and without any waste.

The advantages of my invention are that the material will be preserved from dust, &c., the waste now occasioned in cutting off pieces of paper, &c., in an uneven manner will be entirely avoided; the material can be measured during the operation of drawing it from

the roll; it is suitable for short or long rolls by adjusting the bearings; it is very convenient in its operation and can be furnished at a very reasonable expense, and by painting the interior of the receptacle black it is especially well adapted for preserving photograph and blue print paper.

Having thus described my invention, what I claim, and desire to secure by Letters Patent, is—

1. A conservatory for containing rolls of paper or other fabrics, provided with a cutting-rail having a groove in its upper face, and bearings for revolving the rolls, all constructed and arranged as shown, and substantially as herein described.

2. In a conservatory for rolls of paper or other fabrics, a cutting-rail provided with a groove for the insertion of a knife, and an adjustable partition for different lengths of rolls, substantially as set forth.

3. In a conservatory for rolls of paper or other fabrics, a cutting-rail provided with a groove and a tension device for the paper, substantially as specified.

4. The combination of one or more receptacles for containing rolls of paper or other fabrics, and having a cutting-rail provided with a groove for the insertion of a knife, and arranged on a stand or cabinet, substantially in the manner shown and herein specified.

5. A conservatory for rolls of paper or other fabrics, consisting of a receptacle, *A*, having a movable part for inserting said rolls, and a cutting-rail, *C*, with a groove, *c*, for the insertion of a knife, and provided with adjustable journals, all arranged substantially as and for the purpose set forth.

6. The conservatory herein described, consisting of the receptacle *A*, the movable cover or front for inserting the rolls of paper or other fabrics, and provided with a cutting-rail, *C*, having groove *c* for the insertion of a knife, and an adjustable partition, *D*, all constructed and arranged substantially as and for the purpose specified.

In testimony whereof I hereby affix my signature in presence of two witnesses.

ISAAC MCKIM CHASE.
